CONTROL PANEL FOR A LAUNDRY APPLIANCE

Charles D. Dushek, Lisle, Ill., assignor to General Electric Company, a corporation of New York

Filed Oct. 29, 1959, Ser. No. 58,108

Term of patent 7 years

(Cl. D49—1)

Fig. 1

Fig. 2

Fig. 3

Fig. 4

FIG. 1 is a front perspective view of a control panel for a laundry appliance;

FIG. 2 is a front elevational view thereof;

FIG. 3 is a side elevational view; and

FIG. 4 is a top plan view.

The dominant features of the design reside in the portion shown in full lines.

What is claimed is:

The ornamental design for a control panel for a laundry appliance, as shown and described.
